ENGINE IGNITION MEANS

William L. Nawman, Albany, Calif.

Original application February 17, 1939, Serial No. 256,906. Divided and this application April 5, 1940, Serial No. 327,947

3 Claims. (Cl. 123—143)

This application is a division of my copending application, Serial No. 256,906, filed February 17, 1939 for Engine ignition means.

The invention relates to internal combustion engines and more particularly to an ignition means for internal combustion engines.

An object of the invention is to provide an ignition means for an internal combustion engine which may be embodied as a sturdy, integral part 10 of the engine with all of the parts thereof confined entirely to the engine cylinder and operated automatically by the movement of the engine piston to the head end of the cylinder without the use of any external mechanical or electrical parts as heretofore customarily relied upon for igniting the compressed gas in the engine cylinder.

Another object of the invention is to provide a simple and effective ignition means of the character above which will provide a uniform firing of the compressed gas throughout the entire combustion space of the cylinder.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing the single figure is a vertical sectional view of a part of an internal combustion engine embodying an ignition means constructed in accordance with the present invention.

The ignition means of the present invention consists briefly in the provision of a chamber in the engine in communication with the engine cylinder and into and from which is reciprocated an auxiliary piston which causes the compression and ignition of gases within the chamber, whereupon the ignited gases are passed into the engine cylinder to effect an ignition of the gases therein. In accordance with the present invention the aforementioned relative reciprocal movement of the chamber and auxiliary piston is effected in timed relation to the movement of the engine piston, whereby ignition will take place substantially at a top dead center position of the engine piston in the customary manner. Also, the chamber and auxiliary piston are so formed as to cause a uniform discharge of the ignited products entirely throughout the combustion space of the

engine cylinder, thereby effecting a most complete and effective ignition of the compressed charge of fuel in the cylinder.

With reference more specifically to the accompanying drawing, the engine and ignition means therein depicted comprise an engine casing 6 providing an internal engine cylinder 7 and formed with suitable inlet and discharge passages with valves therein (not shown) for intake of fuel into the cylinder and discharge of spent products therefrom. The engine used in combination with the present device may operate upon either a two or four stroke operating cycle. Mounted within the cylinder 7 is an engine piston 13 which reciprocates to and from the head 14 of the cylinder to operate on the gases in the cylinder in accordance with the cycle of operation of the engine.

The ignition means of the present invention comprises an auxiliary chamber 16 which is arranged in communication with the engine cylinder and a plug member or auxiliary piston 17 which is adapted for movement into and from the chamber to compress explosive gases in the chamber to a self-igniting pressure and drive 25 means is provided for causing the relative reciprocal movement of the member 17 and the chamber 16 in timed relation to the movement of the engine piston 13, so as to cause an ignition of the gases at a proper time in the operating cycle.

In the embodiment of the invention as herein illustrated, the chamber 16 and the member 17 are provided on the engine casing and piston so that the reciprocation of the member 17 into and out of the chamber will be effected in proper timed relation to the movement of the engine piston itself, and without the use of any intervening drive mechanism. As seen in the figure, the chamber 16 is provided in the head end of the engine casing, while the member 17 is provided 40 on the piston.

The chamber 16, as illustrated in the accompanying drawing, is of generally cylindrical shape and is provided with a reduced neck portion 19 at the open end thereof. This latter portion is 45 preferably of cylindrical form and adapted for a sliding fit with a cylinder head portion 21 on the member 17, whereby such head portion on engagement through the neck 19 will cause a compression of the gases contained within the chamber. In accordance with the present construction, the head portion 21 has an axial length somewhat less than that of the chamber and is positioned immediately ahead of a reduced member portion 22, whereby upon movement of the 55

head 21 completely into the chamber as illustrated in the figure, the portion 22 will become aligned with the neck 19, so as to define an annular passage between the portion 22 and the neck 5 for the cylindrical discharge of the ignited products within the chamber. As will be understood, the head portion 21 of the auxiliary piston 21 is of sufficient length relative to the length of the chamber and the volume of the chamber to cause 10 a compression of the fuel gases therein to the point of self-ignition, whereby upon movement of the head portion 21 past the neck 19, such ignited gases will be allowed to pass around the head 21 and out through the annular passage 15 defined between the neck 19 and the reduced portion 22. In this manner a substantially continuous sheet of fire is discharged from the ignition means into all parts of the combustion chamber. Preferably, the axis of the chamber 20 16 and that of the member 17 is coincident with the central axis of the engine cylinder, whereby the discharge of the ignited products will be most effectively distributed throughout the combustion space of the engine cylinder and completely across the head end of the piston.

The chamber 16 is formed in an inserted piece 27 which is set in an opening 28 in the cylinder head and secured in place by means of a lock-washer 29 and nut 31 engaged with a threaded portion of the insert at the outer side of the casing. The auxiliary piston member 17 is attached to the piston 13 for movement therewith and is connected to the head end 32 of the piston in a curved conical base 33 which connects the head end 32 of the piston to the reduced portion 22 of the auxiliary piston. The compressed ignited gases discharged from the chamber 16 flow downwardly from the chamber in a continuous ring of fire and strike the downwardly and outwardly 40 curved surface 33, whereby the ignited gases are spread uniformly across the entire combustion space of the engine cylinder and across the head end of the piston.

I claim:

45 1. In combination with an internal combustion engine having a cylinder and a reciprocating piston therein and fuel inlet and discharge means connected to said cylinder, means communicated with said cylinder and providing a compression chamber formed with a smooth internal cylindrical wall and a cylindrical passage of reduced area 50 opening to said cylinder, a second piston mounted for reciprocation into and from said chamber through said passage and being of cylindrical

form having a substantially sliding fit in said passage and being completely spaced from said chamber wall in inserted position therein for compression and ignition of gases contained therein and formed with an annular recess positioned to register with said passage in an inserted position in said chamber to provide an annular discharge passage for the escape of gases compressed in said chamber, and means causing the interengagement of said chamber and second piston in timed relation to the movement of said first piston.

2. An ignition means for an internal combustion engine comprising, a chamber in communication with the cylinder of the engine and having a reduced open portion, a piston engageable in said chamber to compress and ignite gases therein and having an enlarged head portion having a sliding fit with said chamber reduced portion, said piston head portion having a length 20 less than said chamber so as to move completely into said chamber and uncover said reduced portion to thereby afford an annular discharge passage for the escape of the gases compressed in said chamber, said chamber and piston head 25 portion being formed to define a uniform annular space around said head portion in said chamber, and means causing a relative reciprocal movement of said piston and chamber in timed relation to the movement of the piston of the 30 engine.

3. An internal combustion engine comprising, an engine casing providing a cylinder, a piston reciprocally mounted in said cylinder, said casing being formed with a chamber at the head end 35 of said cylinder having its axis parallel to the longitudinal axis of the cylinder and having a reduced open portion opening into said cylinder, and a member carried by said piston and projecting longitudinally therefrom in substantially 40 coaxial relation with said chamber and having a portion engageable in said chamber and having a sliding fit with said chamber reduced portion to compress and ignite gases in said chamber, said member being reduced in cross-sectional 45 area adjacent said member portion and at a position to register with said reduced chamber portion to provide an annular passage for the discharge of gases from said chamber, said member having a conical base portion connected to said piston for uniformly spreading the gases discharged from said annular passage across the 50 end of the piston.

WILLIAM L. NAWMAN.
